UNITED STATES PATENT OFFICE

JOHN J. TREAT, OF NEW BRITAIN, CONNECTICUT.

LOCK.

SPECIFICATION forming part of Letters Patent No. 660,230, dated October 23, 1900.

Application filed April 6, 1900. Serial No. 11,835. (No model.)

To all whom it may concern:

Be it known that I, JOHN J. TREAT, a citizen of the United States, and a resident of New Britain, county of Hartford, and State 5 of Connecticut, have invented certain new and useful Improvements in Locks and Keys, of which the following is a full, clear, and exact description, whereby any one skilled in the art may make and use the same.

10 The object of this invention is to simplify and cheapen the construction of locks of the class which require two or more keys to operate them, no one of the keys by itself being capable of so doing. The means by which 15 this object is accomplished is shown in the drawings, in which—

Figure 1 is a view of the back of a lock with some of the parts broken away to show the construction. Fig. 2 is an edge view of a 20 lock. Fig. 3 represents the two sections of the key in side view, showing the difference in the bittings. Fig. 4 shows in edge view the two parts of the key together.

It is often advisable, when two or more 25 parties are interested in articles which are kept under lock and key, that the containing package or its lock be so constructed that the package cannot be opened without the presence of at least two of the parties concerned.

30 The safety-deposit box is a case in point, it being customary for both the one who is responsible for the safe-keeping of the box and the owner to have keys, the lock being so constructed that neither key will open the box 35 without the aid of the other. Locks of this kind are generally known in the trade as "guard-key" locks, and this name will be used hereafter to designate such a lock. There are a number of locks now in the market

40 which fill the requirements, but they are very complicated and expensive. In many constructions now in use, I believe, two sets of tumblers are provided and are necessary, one set being operated by each key, and it is the

45 general construction to have one key, called the "guard-key," operate a locking device for the bolt of the lock proper, while the other key operates the bolt as soon as the lock-bolt is released. It will be evident to one familiar

50 with the lock business that to make such a construction as is above suggested there are many difficulties to be overcome and that at

the best the arrangement is bound to be intricate and the manufacture and assembling expensive. By the invention which I will now proceed to describe I have accomplished 55 the desired results and am enabled to produce an effective guard-key lock extremely simple in construction and at a minimum cost.

Referring to the drawings, A denotes the case, B the bolt, C the tumblers, and D the key-guide, of an ordinary lock.

E is the fence on the bolt, which rests against the end of the tumblers c when the bolt is 60 shot and travels back in the gating b in the tumblers when the bolt is withdrawn. This is all according to the ordinary construction of a lock of this class; but it is to be clearly understood that my invention is applicable 65 to any and all descriptions of locks, the one illustrated being used because of its simplicity and adaptability for the purpose of illustration.

My invention consists, essentially, in a lock 70 preferably having but one set of tumblers and a compound key H, made up of a series of elements M N, adapted to operate the tumblers of the lock only when all of the independent elements are present and used simultaneously. Each section of the key has individual bittings, the total number of operative bittings on the several sections being 75 equal in number to the number of tumblers in the lock. It is preferable to use a key made up of not more than two sections, although 80 it is evident that the number of sections is not essential to my invention. In appearance each section of this compound key is itself a key, having a handle, a shank, and 85 bittings. In the key shown in Figs. 3 and 4 each section has individual bittings X Y, which are staggered with the bittings on the other sections, this being one of the many forms in which my invention may be used. 90 Each section of the key has certain duties to perform, and these sections must always be used with a certain relation to one another, and in order to insure the proper positioning of the parts I place some kind of a guard, 95 such as the projection o, on one or more of the parts.

I claim as my invention—

1. A lock-bolt controlled by a single set of

tumblers, in combination with a plurality of independent keys operative simultaneously side by side, the operative bittings of all of which aggregate in number the number of 5 tumblers in the lock.

2. The combination in a lock with the bolt and the tumblers controlling said bolt, of a plurality of independent rotatable keys operative simultaneously side by side, the bit- 10 tings of all of which aggregate in number the number of tumblers in the lock.

3. A lock-bolt controlled by a single set of tumblers mounted upon the same pivot in

combination with a plurality of independent keys operative simultaneously side by side, 15 the bittings of all of which together aggregate in number the number of tumblers in the lock whereby it is necessary to use the keys together to operate the lock.

Signed this 31st day of March, 1900, at New 20 Britain, Connecticut.

JOHN J. TREAT.
